REFRIGERATING APPARATUS

John A. MacLean, Phillipsburg, N. J., assignor to
 Ingersoll-Rand Company, Jersey City, N. J., a
 corporation of New Jersey

Application April 12, 1937, Serial No. 136,387

3 Claims. (Cl. 62—2)

This invention relates to refrigerating apparatus, and more particularly to refrigerating apparatus of the type in which a liquid refrigerant is cooled by partial vaporization.

5 An object of the invention is to reduce the space requirements of refrigerating apparatus while maintaining refrigeration capacity and operating efficiency.

Another object of the invention is to so arrange the parts of a refrigerating construction as to require only low head room.

Other objects will be in part obvious and in part pointed out hereinafter.

In the accompanying drawing in which like numerals denote like parts,

Figure 1 is a longitudinal elevation, partly in section, of refrigerating apparatus constructed in accordance with the practice of the invention.

Figure 2 is a top view, partly in section, of the refrigerating apparatus, and

Figure 3 is a sectional view of a float-controlled switch used in the refrigerating apparatus.

Referring more particularly to Figures 1 and 2 of the drawing, the invention is shown embodied in a water-vapor refrigerating system comprising a closed evaporator vessel 1 wherein water, or other liquid, is subjected to the action of a vacuum to be partially vaporized and cooled, an evacuator 2 to remove vapor from the vessel and 20 to produce the vacuum therein, and a removal pump 3 to impel cooled liquid from the vessel to a place of use (not shown).

The parts so far described are of conventional types, and, as heretofore used, the evacuator has 25 been superimposed on the evaporator and the removal pump has been positioned below the evaporator, thus rendering the overall height of the apparatus considerably in excess of the height of the evaporator. If the available head 30 room at the place of installation is limited, such a construction is at an immediate disadvantage for its height cannot be materially reduced without sacrificing refrigeration capacity and operating efficiency. In the practice of the present invention, however, these disadvantages are overcome and a structure is produced in which the 35 evacuating and pumping means are positioned beside the evaporator and in its longitudinal, rather than vertical, plane.

50 In the illustrated form of the invention, the evaporator vessel 1 is L-shaped comprising a vertical leg closed at one side by a vertical side wall 4 of the vessel and at the top and bottom by spaced horizontal walls 5 and 6 suitably connected to the top and bottom, respectively, of the

side wall 4. The opposite side of the vertical leg is closed at the top by a vertical side wall 7 spaced from and parallel to the wall 4 and depending from the top wall to a point intermediate the top and bottom walls 5 and 6, but opens 5 into the horizontal leg of the vessel below the side wall 7.

The horizontal leg of the vessel is closed at the bottom by the bottom wall 6, at the top by a horizontal wall 8 connected to the bottom of the 10 side wall 7 and at the side by a vertical wall 9 parallel to walls 4 and 7 and connected to the ends of the horizontal walls 6 and 8. Vertical spaced end walls 10, to which all the other walls are connected, are L-shaped to conform to the 15 shape of the vessel and serve to close the ends of the vessel.

The top 8 of the horizontal leg of the vessel is at a considerably lower elevation than the top 5 of the vertical leg and, in the present instance, 20 serves to define a vapor outlet 14 from the vessel and as a support in the horizontal plane of the vessel to which the evacuator 2 is in part affixed in a position adjacent the side wall 7 and in the longitudinal plane of the vessel. The difference 25 in elevation between the top walls 5 and 8 is preferably substantially the same as the height of the evacuator 2 which is shown herein as a centrifugal compressor, and the evacuator is preferably of the type having a bottom inlet 15 which 30 can be connected directly to the vapor outlet 14.

A motor 16 is connected in any suitable way to drive the evacuator 2 and is preferably horizontally aligned with the evacuator and positioned in the longitudinal plane of the vessel 1. Suitable means shown as a horizontal stand 17 which is on a level with and connected at one end to the top 8 of the horizontal leg of the vessel 1 and supported at the other end by legs 18 resting on the supporting surface of the vessel 1, serves 40 to provide an additional support on which the evacuator and motor are mounted.

The evacuator 2 is also provided with a discharge conduit 19 leading to a condenser 20 supported immediately adjacent the evacuator 45 and the evaporator vessel 1 and in the horizontal plane of the vessel. The condenser will be of relatively small size and will not add to the lateral length of the apparatus nor to the 50 height of the apparatus.

The vessel 1 is provided with a vertical transverse partition 21 rising from the bottom wall 6 and spaced between the side walls 4 and 7 to co-operate with the wall 4 and define a vaporization 55

space 11 and a refrigerant outlet well 12 in the vertical leg of the vessel.

5 A refrigerant is admitted to the vessel through suitable means such as a perforated header 22 extending transversely across the vessel in the space 11, above the well 12 and near the top wall 5, and is preferably sprayed toward the adjacent side wall 4. The liquid, vaporizing and cooling as it falls, collects in the well 12 for delivery to 10 an outlet 23 in the side 4 near the bottom of the well and to the inlet of the pump 3 which is connected to the outlet 23 and mounted beside the vessel 1 on a level with the bottom thereof.

15 The height of the vertical leg of the vessel 1 will be great enough to provide sufficient depth of liquid in the well 12 for providing the static head necessary for efficient operation of the pump 3, and to provide a sufficiently large space 11 between the liquid in the well 12 and the header 22 for maintaining refrigeration capacity and efficient vaporization of the incoming liquid.

20 The partition 21 also terminates short of the top wall 5 of the vessel 1 and cooperates therewith and with the walls 6, 7, 8 and 9 to define a vapor outlet passage 13 in the vertical and horizontal legs of the vessel and leading from the space 11 to the vapor outlet 14. The vapor passage 13 is thus within the horizontal plane of the vessel and is L-shaped to extend under the 25 evacuator 2.

30 The passage 13 will serve as a trap for separating liquid from the vapor prior to its entrance to the evacuator 2, for, vapor drawn from the space 11 by the evacuator must first pass downwardly through the vertical leg of the passage into its horizontal leg and then pass upwardly through the outlet 14 into the evacuator. The change in direction of the vapor flow causes the liquid to be hurled from the vapor stream to the 35 bottom of the vapor passage wherein it is collected.

40 Liquid will also collect on the side wall 7 and be drained therefrom. To prevent such liquid from falling into the vapor flowing into the horizontal leg of the passage 13 and being again picked up by such vapor, suitable means such as a small trough 39 may be provided at the bottom of the wall 7. The trough will extend transversely across the vessel 1 and will preferably be open at each end near the end walls 10 to drain into the 45 bottom of the passage 13.

50 Condensate from the condenser 20 may, if desired, be drained through a trap (not shown) into the bottom of the passage 13 and all of the liquid may be discharged into the well 12 to obviate loss of liquid from the system and to obviate flooding of the vapor passage. In the present instance liquid is conveyed from the bottom of the passage 13 through an outlet 24 near the bottom of the side wall 9 to a pump 25, the outlet of which is connected to a pipe 26 which enters the vessel 1 and delivers into the well 12.

55 The pump 25 is supported on a level with the bottom of the evaporator and is preferably driven by an electric motor 27 receiving electricity from wires 28, and the circuit of these wires is controlled by a float-controlled switch actuated by the liquid in the bottom of the vapor passage 13.

60 The float-controlled switch is shown in detail in Figure 3 and comprises a closed bulb 29 into one end of which the wires 28 extend and in which a small quantity of mercury 30 is retained for connecting the wires 28 when the bulb is tilted at one angle and for breaking the connection when tilted in another angle.

65 The bulb 29 is mounted on a lever 31 in a casing 32, and one end of the lever is fulcrumed in the casing. The other end of the lever is pivotally connected to a link 33 which extends through suitable packing in the wall of the casing 32 into an adjacent casing 34 wherein the link is pivotally connected to a lever 35 carrying a float 36.

70 The casing 34 will be mounted beside the vessel adjacent the bottom of the passage 13, and pipes 36 and 37 in communication with the lower regions of the vapor passage 13, as indicated in Figure 1 in dotted lines, open into the bottom and top, respectively, of the casing 34. These pipes serve to admit liquid and vapor to the casing for actuating the float 36 and the switch 29 in accordance with the level of the liquid trapped in the bottom of the passage 13.

75 The effect of the float 36 is to tilt the switch 29 and start the motor 27 and the pump 25 for drawing liquid from the passage 13 whenever the depth of the liquid in the passage exceeds a predetermined degree, and to stop the pump when the level drops. Since the water in the trap portion of the passage 13 has also been cooled 80 by vaporization, discharge thereof into the well 12 will have no material effect on the temperature of the liquid in the well nor will it interfere with the normal operation of the machine.

85 From the foregoing description it will be apparent that an evaporator is provided having sufficient height for efficient operation, and that the pumps, evacuator and condenser do not add appreciably to the height of the apparatus. A compactly arranged structure is thus produced 90 without sacrificing refrigeration capacity or operating efficiency, and the machine may be easily installed in places where the available space, and especially head room is limited.

95 The arrangement as shown is, however, only one of a number of modifications which might be devised and which will be readily apparent to those skilled in the art to which the invention pertains. It is advantageous, however, to have the vapor trap passage 13 defined by walls of the 100 evaporator vessel 1 and the evacuator in part supported thereby for the number of separate parts and the expense of construction can thereby be kept at a minimum.

I claim:

1. In refrigerating apparatus, an evaporator, an inlet for liquid to the evaporator, a well in the evaporator to receive the liquid, a vapor evacuator for the evaporator, means at a side and in a horizontal plane of the evaporator defining a vapor passage from the evaporator to the evacuator and forming a trap in the passage for separating liquid from the vapor, said means also serving as a support for the evacuator, and means including a pump to discharge liquid from the 105 trap in said passage into said well.

2. In refrigerating apparatus, an evaporator, an inlet for liquid to the evaporator, a well in the evaporator to receive the liquid, a vapor evacuator for the evaporator, means at a side and in a horizontal plane of the evaporator defining a vapor passage from the evaporator to the evacuator and forming a trap in the 110 passage for separating liquid from the vapor, said means also serving as a support for the evacuator, and float-controlled means including a pump on a level with the bottom of the evaporator and acting responsively to the amount of liquid in the passage to discharge such liquid into 115 said well.

3. In refrigerating apparatus, an L-shaped evaporator vessel having bottom, top and side walls, a transverse partition in the vertical leg of the vessel cooperating with said walls to define a well in the vertical leg of the vessel and an L-shaped vapor passage in the vertical and horizontal legs of the vessel to act as a trap for separating liquid from the vapor, the well and passage communicating at the top of the vertical leg of the vessel, a vapor outlet from the passage in the top of the horizontal leg of the vessel, an evacuator having a bottom inlet con-

nected to the vapor outlet and supported by the horizontal leg of the vessel, an inlet for liquid to the vessel and delivering into the well, an outlet for liquid at the bottom of the well, a pump on a level with the bottom of the vessel and connected to the last said outlet, and means including a pump on a level with the bottom of the vessel and connected to draw liquid from the bottom of the passage and discharge the same into said well. 5
